United States Patent Office

Des. 181,592
Patented Dec. 3, 1957

181,592

NAPKIN HOLDER OR SIMILAR ARTICLE

Abraham Leifer, Newark, N. J.

Application August 2, 1956, Serial No. 42,489

Term of patent 14 years

(Cl. D44—24)

FIG. 1.

FIG. 2.

Figure 1 is a front perspective view of the napkin holder or similar article embodying my new design, and Fig. 2 is a rear perspective view looking at the holder from the opposite direction.

I claim:

The ornamental design for a napkin holder or similar article, as shown.
